C. OSEAN

FLASH LIGHT

Filed Dec. 26, 1923

UNITED STATES PATENT OFFICE.

CHARLES OSBAN, OF WOODCLIFF, NEW JERSEY, ASSIGNEE TO NATIONAL CARBON COMPANY, INC., A CORPORATION OF NEW YORK.

FLASH LIGHT.

Application filed December 26, 1923. Serial No. 682,668.

To all whom it may concern:

Be it known that I, CHARLES OSBAN, a citizen of the United States, residing at Woodcliff, in the county of Hudson and State of New Jersey, have invented certain new and useful Improvements in Flash Lights, of which the following is a specification.

This invention relates to flashlights or battery hand lamps, and particularly to that type, sometimes called elbow lamps, in which the light beam is projected laterally from the flashlight case instead of from the end thereof, although it will be understood that various features of the present invention may be employed in the latter type of flashlight.

Ordinarily, elbow battery hand lamps are constructed so that the right angle extension that carries the lens and reflector projects a considerable distance outside the outline of the tubular case carrying the same. This is objectionable because it limits the use of the flashlight in narrow spaces, and otherwise detracts from the usefulness and appearance of the flashlight, as by rendering it so top heavy that it is not sufficiently stable to stand in an upright position on its bottom end.

This invention aims to overcome the foregoing objections and to provide a flashlight or elbow lamp in which the right angle extension of the lamp including the lens and lens ring projects but very slightly laterally outside the outline of the case. Other objects of the invention are to provide simplified means for mounting various elements of the flashlight; an improved switch; and an improved means for suspending the flashlight from various supports such as clothing, a nail, etc.

The above and other objects and the novel features of the invention will be apparent from the following description taken with the drawings, in which—

Fig. 1 is a side view of a flashlight embodying this invention;

Fig. 2 is a front view of the head thereof;

Fig. 3 is a sectional view of the head, on an enlarged scale;

Fig. 4 is a detail view;

Fig. 5 is a detail sectional view on the line 5—5 of Fig. 3; and

Fig. 6 is a detail view of the switch mechanism, taken on the line 6—6 of Fig. 1.

Generally speaking, the improved flashlight comprises a tubular case for the battery and switch, an elbow head detachably coupled to the front end of the case carrying the lamp, reflector, lens and their accessories and having the suspending hook for the flashlight secured thereto. As shown, the body C of the casing consists of the usual tubular metal or fiber body that carries the battery B supported at its bottom end upon the usual spiral metal spring (not shown) carried by the cap K that is detachably coupled to the rear end of the body C. A suitable switch S is mounted on the outside of the body C to close the circuit through the lamp and battery to control the lighting of the flashlight.

The front end of the flashlight has the improved elbow head H detachably coupled thereto, as by the screw threads E' shown. The elbow head comprises a substantially cylindrical cupped metal shell that is indented at one side near its closed end and apertured to provide an annular wall W and a ledge W' substantially perpendicular to said wall. The wall W is thus substantially parallel to the axis of the main body C of the flashlight while the axis of the aperture or opening 15 in said wall is substantially perpendicular to such body axis. A shell H having an inturned annular flange H' coextensive with the wall W is secured to the latter, as by rivets 16, so that the opening 15' therein registers with the opening 15, the abutting walls H' and W so thus forming an apertured partition or internal shoulder in the head. The cylindrical wall of the shell H is internally threaded and provides in effect a right-angle cyl-

drical extension for the elbow head to which the threaded lens ring N may be detachably coupled.

The lens ring N has an annular shoulder 5 N' that extends outwardly from the externally threaded part thereof to provide a shoulder for supporting the lens G which may be a bull's-eye as shown, a plain cover glass or of any other section. The lens G is 10 held against the shoulder N' by an inwardly spun front edge N'' of the ring N, thus providing a lens and lens ring attachable and detachable as a unit.

A suitable metal reflector R is mounted in 15 the head E so that its axis is perpendicular to the axis of the main body or casing C and is centrally sleeved and threaded as at R'' to receive the threaded base L' of the usual 20 miniature incandescent lamp L. The reflector R projects through but is spaced from the edges of the registering openings 15 and 15' in the walls W and H', and at its forward end has an outwardly extending flange R' whereby it is supported in opera- 25 tive position. While the reflector may be supported in position and insulated in any desirable way, as shown, it is desirably mounted coaxially within an insulating ring I of rigid material such as fiber or hard 30 rubber. At its rear end the ring I abuts against the shoulder formed by the walls W and H'. At its front end the ring I is provided with an inner shoulder I' against which the rear side of the reflector flange 35 R' abuts, the thinner outer part I'' of the ring I being spun inwardly over the outer edge and the front face of the flange R' to secure the flange and reflector together so that they and the incandescent lamp L 40 may be easily removed and inserted as a unit. This unitary lamp, reflector, and mounting ring assemblage is held in place in the head by the unitary lens and lens ring assemblage already described and by 45 indenting the side wall of the head, as shown, these assemblages may be positioned more closely to the axis of the tubular body C to provide a shorter right angle leg on the head and a flashlight that is more stable 50 when standing upright on its bottom end. When the lens ring is coupled to the head, its threaded part screws into the shell H between the latter and the insulating ring I, and the inner face of the lens G engages the 55 inturned outer end I'' of the insulating ring I and clamps the latter against the shoulder or partition wall formed by the flanges H' and W. The reflector is thus completely insulated from all parts of the casing and 60 rigidly mounted in place.

Various means may be used to electrically connect the lamp L in circuit with the battery B. Since the lamp holder R'' is an integral part of the metal reflector R, a suitable conductor may be connected to either

er of these parts to provide a circuit connection leading to the base L' of the lamp. As shown, a semicircular conductor strip 20 has a radially inwardly extending resilient prong 20' curved or notched at its free end which may engage the outside of the reflector at a point behind the wall W, the latter cooperating with the head E to form a chamber for the contacting elements and rear ends of the reflector and lamp. The 70 fixed end of the conductor 20 is in the form of a right angle, one leg 23 of which is secured to but insulated from the partition W, H' by a rivet 24 and insulating washers 25, 25', 25'', the holes through the leg 23 and 80 said partition being spaced or otherwise insulated from the rivet to avoid contact of metal to metal at these points. The other leg 26 of the conductor 20 is secured to one side of an insulating abutment and contact disk 27 by a metal rivet 28. The insulating disk 27 is held in place against the lower side of a bead 27' in the cylindrical part of the elbow fitting by the legs 23, 26 and the securing rivets 24, 28. 90

The center contact L'' of the lamp is engaged by the free end of a spring contact 29 that is supported on and secured to the disk 27 by metal rivets 29' and 29'', the latter being longer than the rivets 28, 29' and 95 securing a washer 30 to the under side of the disk 27 so that the lower end of the rivet 29'' will engage the center contact B' of the battery B and hold the latter away from the other conducting parts on the disk. A contact plate 31 is secured to the under side of the disk 27 by the conducting rivet 28 and similar rivets 28', and has an opening 31' separating it from the conducting rivets 29', 29''. The plate 31 is engageable in any relative position of the head E and body C by the inturned end 32' of a yieldable strip conductor 32 that is associated with the switch mechanism for controlling the lighting of the lamp. 100

As shown in Fig. 6, the conductor 32 is secured by rivets 33 and 34 to the free end of a stiff strip of insulation 35 that is secured near its other end by rivets 36 and 37 to the inside of the case C. One end of a strip of insulation 38 is secured by the rivet 33 between the outer free end of the insulating strip 35 and the insulating ring 39 that abuts against an interior shoulder 40 in the front threaded part of the casing C, and the other end of the strip 38 passes around the lower edge of the ring 39 and covers the outer end of the rivet 33 to insulate it from the metal casing. The rivet 34 extends outwardly through an opening 42 in the casing C and is insulated from the latter by a washer 34' secured by said rivet. The rivet 34 provides a contact for a circuit closer or spring switch member 43 that is secured to a reciprocal operating member 110 120 125 130

44 by tongues 44' on the latter. An escutcheon member 45 is secured by rivets 46 to the casing and has a depressed rectangular bottom 45' along the upper surface of which the operating member 44 is slideable, and along the lower surface of which the switch member 43 is slideable. The escutcheon provides a housing concealing the switch 43 and rivets 34, 36, 37, and the raised rectangular edge 45'' thereof protects the operating member 44 from accidental operation. An inwardly punched bead or projection 47 in the bottom of the escutcheon is adapted to engage either one of the two holes 47' in the switch member 43 and tends to retain the switch member against accidental displacement from either of its set positions. The circuit may be opened and closed by operating the member 44 in the proper direction to slide the free rounded end of the switch spring 43 onto or from the rivet 34, the latter being also free to yield slightly inwardly because of its position between the securing rivets 33 and 36.

The flashlight may be supported on its bottom cap K or hung from a suitable support to throw its light laterally. As shown, the improved hanger D for hanging the flashlight comprises a strip of resilient metal that is bent at 50 to provide a right-angle extension 51 that is secured to the top wall of the elbow fitting by rivets 51'. The head E has a rounded part E'' at the rear thereof, which is spaced from the bend 50 to provide room for the head of a nail or the like which may be inserted through a hole 52 in the hanger below the bend 50 to suspend the flashlight. Below the hole 52 the hanger is inset as at 53 and secured against the head E by rivets 53'. From the inset 53 the hanger is bent outwardly as at 54 and then downwardly and inwardly to form a long resilient hook 55 adapted to clip over the edge of a pocket, a belt, a windshield and similar supports, the lower end of the hook being turned outwardly to facilitate clipping the hook over an edge.

While a preferred embodiment of the invention has been shown and described in detail, various changes may be made therein without departing from the principles of the invention.

I claim:

56 1. In a flashlight, the combination of a case having a part of its side wall indented longitudinally, current generating means in said case, a lamp in circuit with said means, a reflector cooperating with said lamp, and mounting means for said reflector bearing against said indented part.

2. In a flashlight, the combination of a case having part of its side wall indented longitudinally and an opening through said indented part, current generating means in

said case, a lamp in circuit with said means, a reflector cooperating with said lamp and extending through said opening and means for retaining said reflector in place in said opening.

3. In a flashlight, the combination of a case having a metal part of its side wall indented and an opening through said indented part; a metal coupling member secured to said indented part; a battery in said case, a lamp in circuit therewith; a reflector cooperating with said lamp and extending through said opening, and means retaining said reflector in position comprising a lens and lens ring, the latter being detachably secured to said coupling member.

4. In a flashlight, the combination of a case comprising a tubular body and a head detachably coupled together; a battery in said body; said head having a part of its side wall indented and an opening through said indented part; a lamp in said head; reflector cooperating with said lamp and extending through said opening; a mounting for said reflector bearing against the outside of said indented part; and means holding said mounting in position comprising a lens and lens ring, the latter being detachably coupled to said head.

5. In a flashlight, the combination of a case having an inferior shoulder near its front end, a rigid ring inside said case having one end bearing against said shoulder, a reflector secured to said ring, and means clamping said ring and reflector in said case.

6. In a flashlight, the combination of a case having an inferior shoulder near its front end, a reflector having a flange at its front end, a rigid ring inside said case having one end bearing against said shoulder and having a portion at its other end extending around the edge of said flange to secure said reflector to said ring, a lens or cover glass bearing against said ring, and a member retaining said lens in place and coupled to said case.

7. In a flashlight, the combination of a case; a unitary assemblage therein comprising a lamp, a reflector and a mounting therefor; and a unitary assemblage retaining the aforesaid assemblage in place comprising a lens and a lens ring.

8. In a flashlight, the combination of a case having an inferior shoulder near its front end, a reflector having a flange at its front end, a rigid insulating ring surrounding said reflector and having one end thereof bearing against said shoulder, the other end of said ring having a portion extending inwardly over the outer face of said flange and securing said reflector to said ring, a lens engaging said ring, and a lens ring secured to said lens, connected to said case

- and clamping the lens against said insulating ring.
9. In a flashlight, the combination of a case having an interior shoulder, a reflector, means mounting said reflector on said shoulder, and a conductor secured to said shoulder and in circuit with said reflector.
10. In a flashlight, the combination of a case having an interior shoulder, a battery in said case, a lamp in circuit with said battery, a reflector cooperating with said lamp, means supporting said reflector on said shoulder, a battery contact mounting, and means securing said contact mounting to said shoulder.
11. In a flashlight, the combination of a case comprising a head having an interior shoulder and an interior bead, a battery in said case, a lamp in circuit with said battery, a reflector cooperating with said lamp, insulating means carrying said reflector and bearing against said shoulder, means comprising a lens and lens ring holding said insulating means in place, an insulating disk, contacts on said disk, means electrically connecting said contacts to said lamp and said reflector comprising a conductor securing said disk to said shoulder and holding said disk against said bead.
12. In a flashlight, the combination of a case comprising a head having an interior shoulder and an interior bead disposed in intersecting planes, a battery in said case, a lamp in said head, a reflector cooperating with said lamp and supported in said head so as to reflect light laterally therefrom, a battery contact mounting in said head, and means cooperating with said shoulder and said contact mounting to hold the latter against said bead.
13. In a flashlight, the combination of a case having a head provided with an interior shoulder, a conductor mounting secured in said head, a reflector, a rigid insulating ring supporting said reflector, means including a lens and a lens ring for holding said insulating ring against said shoulder, a lamp mounted in said reflector, and conductors secured to said mounting and in circuit with said lens and said reflector.
14. In a flashlight, the combination of a case comprising a head having an interior shoulder and an interior bead, a battery in said case, a lamp, a reflector cooperating therewith, means mounting said reflector on said shoulder, a battery contact mounting, and means securing said mounting to said shoulder and holding said mounting against said bead.
15. In a flashlight, the combination of a case having an inwardly turned flange; a coupling ring having an inwardly turned flange secured to the first-mentioned flange, thereby providing an annular interior shoulder in the case; a rigid insulating ring within said coupling ring bearing against said shoulder, a reflector secured within said insulating ring, and means comprising a lens and a lens ring cooperating with said coupling ring to clamp said insulating ring and reflector in place.
16. An elbow head for a flashlight comprising a cupped shell having means at one end to fit a tubular flashlight case and having its side wall indented adjacent its other end and an opening in such indented part.
17. An elbow head for a flashlight comprising a cupped shell having its side wall indented and an opening formed in such indented portion, the axis of such opening being perpendicular to the main axis of the shell, a threaded coupling ring secured in front of said indented wall, and a lens ring removably threaded to said coupling ring.
18. In a flashlight, the combination of a casing body and head detachably coupled together, and a hanger for the flashlight comprising a metal strip rigidly secured to said head, said strip having a hole therein above and a resilient hooking clip below such securing means.
19. In a flashlight, the combination with a casing having a detachable head, of a hanger for the flashlight secured to the top and side walls of said head, said hanger having a hole therein between such top and side securing means and a hook below such side securing means.
20. In a flashlight, the combination with a casing having an opening through its wall, conductive means exposed by said opening and extending within said casing, a switch member movable to engage said conductive means, and yieldable means in said casing yieldingly supporting said conductive means at said opening.
21. In a flashlight, the combination of a casing, an insulating strip secured near one end within said casing, a conductive strip, conductive means securing one end of the latter to said insulating strip, and a switch member cooperating with such conductive securing means, the latter and the parts of the strips connected thereby being yieldable upon engagement by said switch member.
22. In a flashlight, the combination of a metal case; an insulating ring therein; a conductive strip; an insulating strip between said conductive strip and said case; means securing said strips to said ring; means securing one end of said insulating strip to said case; conductive means securing said strips together between said ring and the means that secures said insulating strip to said case; a resilient switch member adapted to engage such conductive securing means; operating means for said switch member; and a metal escutcheon secured to said case, housing said switch mem-

ber, and providing a mounting for said switch in which said conductive means comprises operating members.

23. The invention as set forth in claim 20, in which said yieldable means comprises a strip of insulating material fixed at its opposite ends.

24. The invention as set forth in claim 20,

a conductive strip secured in said casing and a rivet disposed in said opening and securing said strip to said yieldable means. 10

In testimony whereof, I affix my signature.

CHARLES OSEAN.
